UNITED STATES PATENT OFFICE.

BERT G. LA BAR, OF TURTLE CREEK, PENNSYLVANIA.

DESIGN FOR A TRAFFIC SIGNAL LAMP.

Application filed December 15, 1924. Serial No. 11,704. Term of patent 7 years.

To all whom it may concern:

Be it known that I, BERT G. LA BAR, a citizen of the United States of America, residing at Turtle Creek in the county of Allegheny and the State of Pennsylvania, have invented a certain new, original, and ornamental Design for Traffic Signal Lamps, of which the following is a specification, reference being had to the accompanying drawing, forming a part hereof.

Fig. 1 of the accompanying drawing is a front elevational view of a traffic signal

lamp for vehicles, showing my new design;

Fig. 2 is a rear elevational view of the lamp shown in Fig. 1; and

Fig. 3 is a side elevational view of the lamp shown in Figs. 1 and 2.

I claim:

The ornamental design for a traffic signal lamp as shown.

In testimony whereof, I have hereunto subscribed my name this 5th day of December, 1924.

BERT G. LA BAR.
